FIGURE 1 is a top plan view of a suction cleaner showing my new design;

FIGURE 2 is a side elevational view, the opposite side being substantially similar;

FIGURE 3 is a rear elevational view thereof;

FIGURE 4 is a front elevational view thereof;

FIGURE 5 is a top front perspective view of the cleaner;

FIGURE 6 is a top plan view of a modified form of the suction cleaner shown in FIGURE 1;

FIGURE 7 is a side elevational view, the opposite side being substantially similar, of the modified form of the suction cleaner shown in FIGURE 6;

FIGURES 8 and 9 are respectively rear and front elevational views of the modified form of the suction cleaner shown in FIGURES 6 and 7, and

FIGURE 10 is a top front perspective view of the

modified form of suction cleaner shown in FIGURES 6 to 9 inclusive.

The elements shown in broken lines in FIGURES 5 and 10 are omitted from the remaining figures for convenience of illustration.

The dominant features of my design reside in the portions of the drawings shown in full lines.

This application is a continuation of my design applications Serial Nos. D. 63,716 and D. 63,717 both filed on January 26, 1961, and now abandoned.

I claim:

The ornamental design for a suction cleaner, substantially as shown and described.
